(57) **CLAIM**

The ornamental design for a baseball tee, as shown and described.

DESCRIPTION

FIG. 1 is a perspective view of the baseball tee showing the claimed design;

FIG. 2 is a front elevational view of the baseball tee shown in FIG. 1, the back elevational view, the left-side elevational view, and the right-side elevational view being a mirror image of the front elevational view;

FIG. 3 is a bottom plan view of the baseball tee shown in FIG. 1; and,

FIG. 4 is a top plan view of the baseball tee as shown in FIG. 1.

The broken lines in the figures show portions of the baseball tee that form no part of the claimed design.
